UNITED STATES PATENT OFFICE.

WILLIAM C. WEAVER, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed December 27, 1918. Serial No. 268,444.

To all whom it may concern:

Be it known that I, WILLIAM C. WEAVER, a citizen of the United States, residing at East Orange, in the county of Essex, State 5 of New Jersey, have invented certain new and useful Improvements in Telephone-Exchange Systems, of which the following is a full, clear, concise, and exact description.

This invention relates to telephone exchange systems, and more particularly to 10 such systems in which the successive assistance of a plurality of operators is required in establishing a connection between two telephone lines.

15 It is frequently the practice, especially in toll or long distance telephone systems, for one operator upon answering a call over a trunk circuit associated with a calling line, to obtain certain information, and furnish 20 such information to another operator, who thereupon connects with the trunk and completes the connection with the called line, or refers the matter to another operator who is able to complete the connection.

25 In systems of this character, it is essential that each operator receive a positive and accurate indication when a succeeding operator establishes a connection with the calling line so that the previous connection 30 therewith may be discontinued.

It is an object of this invention to provide 35 a simple and inexpensive system of this nature which, while providing a reliable disconnect signal for an operator when the responsibility of the call has been assumed 40 by the succeeding operator, irrespective of the character of the link circuit employed, also insures the restoration to normal of all apparatus in the link circuit upon the disconnection of such circuit from the line 45 circuit.

In order to attain this object, in accordance 50 with one feature of the invention, a link circuit employed by an operator for connection with the trunk circuit associated with a calling line is provided with a differentially wound relay, the normally aiding windings of which are placed in an opposing relation within a local circuit upon the opening of the operating circuit, thereby 55 insuring the immediate release of such relay.

It is thought that the invention may be 60 thoroughly understood from the following specification and the annexed drawing, in 65 which is shown one embodiment of the in-

vention as applied to an operator's link circuit.

In the drawing an ordinary subscriber's line circuit A is connected in any well-known manner at a central office with a 60 trunk circuit B terminating in multiple jacks 1, 2 and 3, appearing at various operators' positions X, Y and Z, respectively, of the switchboard at the central office. At 65 positions Y and Z similar operator's link circuits D' and D respectively, embodying the invention are provided to enable the operators thereat to secure connection with the trunk circuit B. At position X, sufficient 70 portions are shown of an ordinary connecting or link circuit C which may be of any usual type employed for connecting the called line circuit (not shown) with the trunk circuit B. Relays 9, 12, 13 and 15 of link circuit D, and relays 109, 112, 113 75 and 115 of link circuit D', cooperate to control the disconnect signal lamps 18 and 118 respectively, the windings of marginal relays 9 and 109, which are connected in 80 magnetically aiding relationship upon the connection of the associated plug with the corresponding jack of the trunk circuit B being changed to a magnetically opposing relationship upon the disconnection of the associated plug from the corresponding 85 jack of the trunk circuit, thereby aiding the release of the relay. In order to indicate that relays 12 and 112 are slow to operate, the drawing shows arrows intersecting the armatures of such relays and arrows 90 pointing in the direction in which the armatures move slowly.

It is thought that the invention will be 95 more fully comprehended from the following description of the operation of the system illustrated by the drawing.

Assuming that a call initiated at the subscriber's station on the line A in the usual manner has been answered, and the line connected in any well-known manner with the 100 trunk circuit B, then the operator at position Z, who may be the recording or other toll operator, upon being notified over a call circuit or in some other suitable manner, that the calling line is connected with the 105 trunk circuit B, inserts the plug 7 of the operator's link circuit D into jack 3. Relay 9 operates over a circuit established from battery through the winding 8 of relay 9, the sleeve contacts of plug 7 and jack 3 and 110

resistance 4 to ground. Relay 11 thereupon operates over a circuit extending from battery through the winding of relay 11, and the contact of relay 9 to ground. The opening of the upper normal contact of relay 11 disconnects the testing conductor of the operator's telephone set from the tip contact of plug 7, and the closure of the upper alternate contact thereof completes the continuity of the tip conductor to the listening key 19. The closure of the lower alternate contact of relay 11 connects the winding of marginal relay 13 to ground, which, however, does not obtain sufficient current from the sleeve circuit to operate. Slow operating relay 12 operates over a circuit established from battery through the winding of relay 12, the contact of relay 13, contact 17 and the lower alternate contact of relay 11 to ground. A circuit is thereupon completed from battery through windings 14 and 16, in series, of relay 15 and the right-hand alternate contact of relay 12 to ground. By the operation of relay 12, the circuit of a Wheatstone bridge is completed, the arms of which are the windings 14 and 16 of relay 15, the resistance 4, and the winding 8 of relay 9. In the galvanometer circuit is connected winding 10 of relay 9. Grounded battery is connected to the junction of arms 14 and 8, and ground to the junctions of 4 and 16.

Relay 15 is differentially connected and does not operate under these conditions, and the current flows through winding 10 in such a direction that the energizing effect of such winding aids that of winding 8 in maintaining relay 9 in an operated condition. The actuation of listening key 19 connects the operator's telephone set (not shown) with the link circuit conductors in the usual manner and through the trunk circuit B with the line circuit A thereby enabling the operator to converse with the calling party.

If the operator at position Z has obtained sufficient information, the connecting operator at position X may be notified over a call circuit or in any other suitable manner, and the call may be completed by the latter operator. However, the call may be referred by the operator at position Z to another operator, such as the operator at position Y, for further information.

In the latter case the operator at position Y, in response to such notification, inserts plug 107 of link circuit D' into jack 2 of trunk circuit B, thereupon operating relay 109 over a circuit established from battery through winding 108 of relay 109, and the sleeve contacts of plug 107 and jack 2 to the sleeve conductor of the trunk circuit B where it joins the circuit previously traced, including the winding 8 of relay 9. Relay 111 also operates over a circuit established

from battery through the winding of relay 111 and the contact of relay 109 to ground. Marginal relay 113, which is similar to relay 13 of link circuit D and corresponds thereto, is energized in this circuit with sufficient current for operation. Due to the slow operating character of relay 112, relay 113 operates over a circuit established from battery connected to the sleeve contacts of plug 7, and jack 3 through the windings 14 and 10 of relays 15 and 9, respectively, in series, and the winding 8 of relay 9 through the sleeve conductor of the trunk circuit B, the sleeve contacts of jack 2 and plug 107, the normal contact of relay 112, the winding of relay 113, and the lower alternate contact of relay 111 to ground. The operation of relay 113 opens the circuit of, and prevents the complete operation of relay 112. Under these conditions the current flowing through windings 14 and 16 of differential relay 15 causes the operation of such relay, whereupon disconnect signal lamp 18 is lighted over a circuit extending from battery through the contact of relay 15 and lamp 18 to ground, thereby indicating that the responsibility of the call has been assumed by the operator at position Y.

The operator at position Z thereupon removes the plug 7 from the jack 3, opening the operating circuit of relay 9, whereupon a circuit is established from battery through winding 8 of relay 9, the left-hand alternate contact of relay 12, winding 10 of relay 9 to the mid point between windings 14 and 16 of relay 15 where it joins the circuit previously traced for windings 14 and 16. Relay 9 releases in this circuit, the release being assisted by the reversal of current in winding 10. Relays 11, 12 and 15 thereupon release, extinguishing the lamp 18 and restoring all apparatus of link circuit D to normal. The winding of marginal relay 113 of link circuit D', is thereupon included in a circuit extending from battery through winding 108 of relay 109, the left-hand normal contact of relay 112, the winding of relay 113, and the lower alternate contact of relay 111 to ground, but the amount of current flowing through such circuit is insufficient to maintain relay 113 operated. In releasing its armature, relay 113 causes the operation of relay 112 over a circuit established from battery through the winding of relay 112, the contact of relay 113, and contact 117 of relay 111 to ground, thereby placing the apparatus of link circuit D' in the same condition as that of the similar apparatus of link circuit D existing upon the insertion of plug 7 into jack 3. As in the case of link circuit D the actuation of listening key 119 connects the operator's telephone set (not shown) at position Y with the line circuit A through the link circuit D', and the trunk circuit B. After obtaining the re-

quired information the operator at position $\bar{Y}$ notifies the connecting operator at position $\bar{X}$, over a call circuit or in some other suitable manner, and the latter operator proceeds to complete the connection from the trunk circuit B to the called line. In establishing this connection, the insertion of the answering plug 5 of link circuit C into jack 1 of the trunk circuit B completes a circuit 5 extending from battery through resistance 6, sleeve contacts of plug 5 and jack 1 to the sleeve conductor of trunk circuit B , where it joins the circuits previously traced as being connected with such sleeve conductor 10 through the sleeve contacts of plug 107 and jack 2. Under these conditions the current flowing through the differentially connected windings 114 and 116 causes the operation of relay 115 and the consequent 15 lighting of lamp 118 over a circuit extending from battery through the contact of relay 115, and the lamp 118 to ground. The operator at position $\bar{Y}$ observing the illumination of lamp 118, removes the plug 107 20 from jack 2, whereupon, in a manner similar to that described in connection with the removal of plug 7 from jack 3, the operating circuit of relay 109 is opened, the windings 108 and 110 are placed in opposing relation 25 in a local circuit, thereby causing the release of such relay and the consequent restoration to normal of all apparatus of link circuit D' .

It will thus be evident from the above description that by means of this system a positive disconnect indication is given to each operator upon the assumption of the responsibility for the call by the succeeding operator, and that the complete and immediate restoration to normal of all apparatus in the link circuit is insured upon the disconnection of the link circuit.

What is claimed is:

1. A telephone exchange system comprising a trunk line circuit, an operator's link circuit for connection therewith, a relay in such link circuit having a plurality of windings and operated through one winding upon the connection of the link circuit with the trunk circuit, and means for connecting such windings in magnetically aiding relationship upon such connection to maintain the relay operated, and for connecting such windings in another circuit upon the disconnection of the link circuit from the trunk circuit to release the relay, the windings being connected in magnetically opposing relationship.

2. A telephone exchange system comprising a trunk line circuit, an operator's link circuit for connection therewith, a relay having a plurality of windings and operated through one winding upon the connection of the link circuit with the trunk circuit, and means controlled by such con-

nnection for also connecting another of such windings in magnetically aiding relationship with the first mentioned winding to maintain the relay in an operated condition, and for alternatively connecting such windings in another circuit to cause the release of the relay, the windings being connected in magnetically opposing relationship.

3. A telephone exchange system comprising a trunk line circuit, an operator's link circuit for connection therewith, a relay having a plurality of windings and operated through one winding upon the connection of the link circuit with the trunk circuit, a circuit therefor for maintaining the relay in an operated condition established upon and controlled by the connection of the link circuit with the trunk circuit, and including certain of such windings connected in magnetically aiding relationship, and a releasing circuit for the relay completed upon the opening of the operating circuit and including the same windings connected in magnetically opposing relationship.

4. A telephone exchange system comprising a trunk line circuit; an operator's link circuit for connection therewith; a relay having a plurality of windings; an operating circuit therefor, completed upon the connection of the link circuit with the trunk circuit, and including one of such windings and conductors of the trunk and link circuits; a maintaining circuit for such relay, subsequently completed during such connection, including another of such windings connected in magnetically aiding relationship with the first mentioned winding; and a releasing circuit for the relay established upon the disconnection of the link circuit from the trunk circuit independent of the conductors of such trunk and link circuits, and including the above mentioned two windings connected in magnetically opposing relationship.

5. A telephone exchange system comprising a trunk line circuit, an operator's link circuit for connection therewith, a relay having a plurality of windings and operated through one winding upon the connection of the link circuit with the trunk circuit, a circuit for maintaining such relay operated completed during the connection of the trunk and the link circuits including two such windings and means for connecting such windings in another circuit to release the relay, the direction of current flowing through one of such windings being reversed upon the disconnection of the link from the trunk.

6. A telephone exchange system comprising a trunk line circuit, a plurality of similar operator's link circuits for connection to said trunk circuit, a relay in each link

- circuit with a plurality of windings, means for connecting the windings of said relay in magnetically opposing relationship upon the connection of its associated link circuit 5 with the trunk circuit to prevent its operation under this condition, and means for changing the relative current flow in the windings to cause the operation of said relay upon the connection of the second link 10 circuit with the trunk circuit.
7. A telephone exchange system comprising a trunk line circuit, a plurality of similar operator's link circuits for connection to said trunk circuit, a marginal relay in each link circuit, means for preventing the operation of said relay when its associated link circuit is connected with said trunk circuit and said link circuit is the first to be connected thereto, means for preventing 15 its subsequent operation when a second one of said plurality of link circuits is connected to the trunk circuit, and means for caus-
- ing the operation of said marginal relay when its associated link circuit is the second of said link circuits to be connected 20 with said trunk circuit.
8. In a telephone exchange system, a trunk circuit, a link circuit for connection therewith, a relay having a plurality of windings and operated through one of the windings upon the connection of the link circuit with the trunk circuit, and means responsive to such connection for connecting another of the windings in magnetically aiding relationship with the first mentioned 25 winding to assist in maintaining the relay operated and effective upon the disconnection of the link circuit from the trunk circuit to release the relay.

In witness whereof, I hereunto subscribe 40 my name this 24th day of December A. D., 1918.

WILLIAM C. WEAVER
